(57) **CLAIM**

The ornamental design for a disposable glove, as shown and described.

DESCRIPTION

FIG. 1 is a top plan view of a disposable glove showing their new design; the bottom view being a mirror image thereof; FIG. 2 is a top plan view of a first alternate embodiment of the disposable glove; the bottom view being a mirror image thereof;

FIG. 3 is a top plan view of a second alternate embodiment; the bottom view being a mirror image thereof, and,

FIG. 4 is a top plan view of a third alternate embodiment; the bottom view being a mirror image thereof.

The thickness of the disposable glove forms no part of the claimed design.

The broken lines indicate unclaimed portions of the disposable glove.

The long-short-short broken lines in the drawings which define the bounds of the claimed design form no part thereof.
